AMPHIBIOUS VEHICLE BODY

Bernard Michael Flaherty, 2271 Horseshoe Drive,
Birmingham, Mich. 48010

Filed Mar. 24, 1969, Ser. No. 16,421

Term of patent 3½ years

Int. Cl. D12—13

U.S. Cl. D71—1

FIG. 1 is a plan view of the amphibious vehicle body showing my new design.

FIG. 2 is a side elevational view thereof, both sides of the vehicle presenting a similar though opposite aspect.

FIG. 3 is a bottom view of the amphibious vehicle body.

FIG. 4 is a rear end view.

FIG. 5 is a front end view.

I claim:

The ornamental design for an amphibious vehicle body, as shown and described.
